UNITED STATES PATENT OFFICE.

JOHN E. FARNSWORTH, OF BAZINE, KANSAS, ASSIGNOR TO FARNSWORTH & WILLIAMS, OF SAME PLACE.

COMBINATION-LOCK.

SPECIFICATION forming part of Letters Patent No. 447,639, dated March 3, 1891.

Application filed October 18, 1890. Serial No. 368,548. (Model.)

To all whom it may concern:

Be it known that I, JOHN E. FARNSWORTH, of Bazine, in the county of Ness and State of Kansas, have invented a new and Improved 5 Combination-Lock, of which the following is a full, clear, and exact description.

The object of the invention is to provide a new and improved combination-lock which is simple and durable in construction and 10 permits of a great number of changes, thus making it impossible to open the lock without knowing the combination.

The invention consists of a series of levers adapted to engage and disengage the locking-bolt, a series of cams for actuating the said levers, and a train of gear-wheels for actuating the said cams at different rates of 15 speed.

The invention also consists of certain parts 20 and details and combinations of the same, as will be fully described hereinafter, and then pointed out in the claims.

Reference is to be had to the accompanying drawings, forming a part of this specification, 25 in which similar letters of reference indicate corresponding parts in all the figures.

Figure 1 is a front view of the improvement. Fig. 2 is a like view of the same with the front plate of the casing removed and 30 parts in section. Fig. 3 is a transverse section of the same on the line 3 3 of Fig. 2. Fig. 4 is an enlarged sectional side elevation of the pointers and adjacent parts. Fig. 5 is a face view of a pawl-and-ratchet mechanism. Fig. 6 is a perspective view of one of 35 the cam-wheels.

The improved combination-lock is provided with a suitably-constructed casing A, in which is fitted to slide the locking-bolt B, provided 40 at its under side, inside of the casing, with rack-teeth B', in mesh with a gear-wheel C, held on the knob-spindle D, mounted to turn in the usual manner in the casing, and provided with an indoor knob D' and an outdoor 45 knob D".

At the inner end of the locking-bolt B is secured a plate B", adapted to travel on top of a series of levers E, F, and G, all fulcrumed on a pin A', arranged transversely in the casing A, and provided with shoulders on their upper sides. The under sides of the levers

E, F, and G are curved, as is plainly illustrated in Fig. 2, and are adapted to travel or ride on the peripheries of the cam-wheels E', F', and G', each of which is circular, with a 55 notch in its periphery, (see Fig. 6,) in which notch rests the under side of the respective lever E, F, or G, so as to hold the latter in a lowermost position to permit the back plate B" to freely travel over the levers. When 60 the bolt B has been moved into its outermost position by turning either of the knobs D' or D", and one of said cams is turned so as to raise the respective lever E, F, or G, then the latter extends at its free end in front of 65 the plate B", so that a return movement of the bolt B is impossible.

The cam-wheel E' is mounted to turn loosely on a shaft H, extending through the casing and carrying at its ends pointers H', adapted 70 to indicate on dials I and I', respectively secured or formed on the inside and outside of the casing A. On the face of the cam-wheel E' is formed or secured a pinion E", meshing into a gear-wheel J, secured on a shaft J', extending transversely and mounted to turn in suitable bearings in the casing A. The gear-wheel J meshes into a pinion K, provided with a sleeve K', having a square opening into which extend the knob-spindles K", carrying at their outer ends the indoor knob K" and the outdoor knob K', respectively. By turning either of the knobs K" or K' the pinion K is revolved, so that the latter imparts a rotary motion to the gear-wheel J, which by 85 meshing into the pinion E" turns the cam-wheel E', so as to change the position of the lever E, riding on the said cam-wheel. On the shaft J' is secured another gear-wheel J", similar in size to the gear-wheel J and meshing 90 into a pinion L, mounted to turn loosely on the shaft H and provided with a hub L', on which is secured a pointer L", also adapted to indicate on the inner dial I.

The cam-wheel E' is provided with a hub 95 E", extending outward and similar to the hub L'. On this hub E" is also secured a pointer L", which indicates on the outer dial I', the two pointers L" standing in the same relative position. Thus when either of the knobs K" or K' is turned, the cam-wheel E' is turned, and the pointer L", carried by its hub E", changes its

position on the dial I, and the other pointer L² on the hub L' of the pinion L moves in the same ratio on the inner dial I, so that when the operator ceases to turn either of the knobs 5 K³ or K⁴ the two pointers L² stand over the corresponding numeral on the dials I and I'. On the shaft J' are also secured pinions J³ and J⁴, of the same size, and of which the pinion J³ meshes into a gear-wheel F², secured or 10 formed on the cam-wheel F'. The latter is provided with a hub F³, on which is secured a pointer F⁴, indicating on the outer dial I. The other pinion J⁴ meshes into a gear-wheel I⁵, similar in size to the gear-wheel F² and 15 held concentric with the cam-wheel E'. The hub F⁶ is formed on this gear-wheel F⁵ and carries a pointer F⁴, which stands in the same position as the other pointer F⁴, but indicates on the outer dial I'. When either of the 20 knobs K³ or K⁴ is turned, the rotary movement imparted to the shaft J', as previously described, causes the two pinions J³ and J⁴ to turn the gear-wheels F² and F⁵, so that their two pointers F⁴ move simultaneously 25 and the same distance on the inner and outer dials I and I'. On the shaft J' is also secured a pinion J⁵, which meshes into a gear-wheel N, mounted to turn loosely on the shaft H and carrying a spring-pawl N', in mesh 30 with a ratchet-wheel O, secured on the shaft H, on which is also secured the cam-wheel G', previously mentioned. Thus when either of the knobs K³ or K⁴ is turned in one direction the pinion J⁵ is rotated and imparts a rotary 35 motion to the gear-wheel N, which, by its pawl N' engaging ratchet-wheel O, turns the latter, and consequently the shaft H, so that the pointers H' move in the direction of the arrow a' on the dials I and I'. When the knobs 40 K³ or K⁴, however, are turned in an opposite direction, the pawl N' of the revolving gear-wheel N glides over the teeth of the ratchet-wheel O, and the latter, as well as the shaft H and its pointers H', remains stationary. 45 In order to prevent an accidental displacement of the shaft H, the cam-wheel G' is provided with a ratchet-wheel P, adapted to be engaged by a pawl P', fulcrumed on the pin A', as is plainly illustrated in Fig. 2. The 50 pawl P' holds the ratchet-wheel P in place, thus preventing the turning of the shaft H and its pointers H' when the knobs K³ and K⁴ are turned in the reverse direction above mentioned. The pawl P' is so arranged as to glide 55 over the teeth of the ratchet-wheel P when the shaft H turns in the direction of the arrow a', above mentioned. It is understood that the two pointers H' indicate over the same numerals on the dials I and I'. 60 The operation is as follows: When the three cam-wheels E', F', and G' are in such a position that their notches stand on top, as illustrated in Fig. 2, then the levers E, F, and G are in their lowermost position and the bolt 65 B can be freely moved inward or outward as the bottom of the plate B² travels on top of the said levers. The several pointers con- nected with the respective cam-wheels and their levers are adjusted in such a relative position as to indicate on the dials I and I' 70 the respective numerals forming the combination of the lock. As illustrated in Fig. 1, the combination is "15 30 45"—that is to say, the pointers H' stand over the numerals "15" on the dials I and I' and are shifted only in 75 the direction indicated by arrow a' when the shaft H is turned. The pointers L² stand at the numerals "30" on the dials I and I' and change their position when either of the knobs K³ or K⁴ is turned in either direction. 80 The pointers F⁴ stand at the numerals "45" on the dials I and I' and are also turned when the knobs K³ and K⁴ are turned in either direction. When the knobs K³ and K⁴ are turned in the direction of arrow b', 85 the pointers H' remain stationary, while the pointers L² and F⁴ move in the inverse direction of the arrow a', and the pointers L² at the same time move considerably faster than the pointers F⁴, owing to the differential 90 gear-wheels connecting the pointers with the pinion K, operated by the knobs K³ and K⁴. Now when the bolt B is in the innermost position and the operator turns either of the knobs K³ or K⁴ in the inverse direction of arrow b', then the cam-wheels E', F', and G' are turned, thus raising the levers E, F, and G, whereby the back plate B² is engaged by 95 the inner shoulders of the said levers and an outward movement of the bolt B is prevented. 100 The knobs D' and D² cannot be turned. The turning of the knobs K³ or K⁴ in the direction indicated changes the position of the pointers H', L², and F⁴, and when the operator desires to unlock the bolt B, so as to move it 105 into an outermost position, he has to turn either of the knobs first in the inverse direction of the arrow b' until the pointers H' again indicate or stand over the numerals "15" and the notch in cam-wheel G' is on top, thus 110 holding lever G in its lowermost position. The operator then reverses the movement of the respective knobs K³ or K⁴, so as to turn the same in the direction of the arrow b' until the slow-moving pointer L² is turned to 115 numeral 30. The notches in the cam-wheels E' and F' then again stand on top and the levers E and F have dropped into their lowermost position by their own weight. The bolt B can now be moved outward by turning 120 either of the knobs D' or D², and when the door is locked the operator turns either of the knobs K³ or K⁴ in the inverse direction of the arrow, so as to again actuate the cam-wheels E', F', and G' to swing the levers E, 125 F, and G upward. The outer free ends of the said levers now abut against the back plate B², thus preventing a return movement of the bolt B. By the turning of the knobs K³ and K⁴ the pointers H', F⁴, and L² have 130 changed their positions on the dials I and I'. The bolt can be unlocked by turning either of the knobs K³ or K⁴, as above described, until the pointers H', F⁴, and L² have moved to their

proper position—that is, over the numerals "15," "45," and "30," respectively, on the dials I and I'. The pointers and dials are covered by glass. In order to change the combination, the operator either removes the front plate or the entire lock from the door, so as to get access to the working parts. The cam-wheels are then held in place with the notches in an uppermost position, and the operator now shifts the sets of pointers H', F', and L² on the shaft II and the sleeves F³ and L', respectively, care being taken to move the two pointers of each set to the same numeral desired to form part of the combination.

15 Having thus fully described my invention, I claim as new and desire to secure by Letters Patent—

1. In a combination-lock, the combination, with a series of levers adapted to engage or disengage the locking-bolt, of a series of cam-wheels adapted to actuate the said levers, and means, substantially as described, for moving some of the said cam-wheels in both directions and one only in one direction, substantially as shown and described.

2. In a combination-lock, the combination, with a series of levers adapted to engage or disengage the locking-bolt, of a series of cam-wheels adapted to actuate the said levers, means, substantially as described, for moving some of the said cam-wheels in both directions and one only in one direction, and pointers connected with the said cam-wheels and indicating on dials, substantially as shown and described.

3. In a combination-lock, the combination, with a series of levers adapted to engage or disengage the locking-bolt, of a series of cam-wheels adapted to actuate the said levers, means, substantially as described, for moving some of the said cam-wheels in both directions and one only in one direction, pointers connected with the said cam-wheels and indicating on dials, and a train of gear-wheels connecting the said cam-wheels with the said pointers to move the latter at a different rate of speed, substantially as shown and described.

4. In a combination-lock, the combination, with a series of levers adapted to engage or disengage the locking-bolt, of a series of cam-wheels adapted to actuate the said levers, means, substantially as described, for moving some of the said cam-wheels in both directions and one only in one direction, pointers connected with the said cam-wheels and indicating on dials, a train of gear-wheels connecting the said cam-wheels with the said pointers to move the latter at a different rate of speed, and a knob-spindle carrying a pinion in mesh with the said train of gear-wheels, substantially as shown and described.

5. In a combination-lock, the combination, with a series of levers adapted to engage or disengage the locking-bolt, of a series of cam-wheels adapted to actuate the said levers, and

a train of gear-wheels for actuating the said cams at different rates of speed, substantially as shown and described.

6. In a combination-lock, the combination, with a series of levers adapted to engage or disengage the locking-bolt, of a series of cam-wheels adapted to actuate the said levers, a train of gear-wheels for actuating the said cams at different rates of speed, and a knob-spindle provided with an indoor and outdoor knob and carrying a pinion in mesh with the said train of gear-wheels for actuating the lock, substantially as shown and described.

7. In a combination-lock, the combination, with a bolt provided with a back plate, of a series of pivoted levers provided with shoulders on their upper sides and upon the upper sides of which the back plate is adapted to travel, and a series of cam-wheels for operating the said levers, substantially as and for the purpose set forth.

8. In a combination-lock, the combination, with a bolt provided with a back plate, of a series of levers adapted to engage the said back plate in an innermost or outermost position of the said bolt to lock the latter in place, a corresponding series of cam-wheels adapted to actuate the said levers to engage said levers with the back plate or disengage them from the same, a train of gear-wheels for actuating the said cam-wheels at different rates of speed, and a knob-spindle carrying a pinion in mesh with the said train of gear-wheels, substantially as shown and described.

9. In a combination-lock, the combination, with a bolt provided with a back plate, of a series of levers adapted to engage the said back plate in an innermost or outermost position of the said bolt to lock the latter in place, a corresponding series of cam-wheels adapted to actuate the said levers to engage said levers with the back plate or disengage them from the same, a train of gear-wheels for actuating the said cam-wheels at different rates of speed, a knob-spindle carrying a pinion in mesh with the said train of gear-wheels, and sets of pointers connected with the said cam-wheels and adapted to indicate on suitable dials, substantially as shown and described.

10. In a combination-lock, the combination, with a cam-wheel and a lever actuated by the said cam-wheel, of a pawl-and-ratchet mechanism connected with the said cam-wheel, a gear-wheel carrying the pawl of the said mechanism, and a train of gear-wheels in mesh with the said gear-wheel, substantially as shown and described.

11. In a combination-lock, the combination, with a cam-wheel and a lever actuated by the said cam-wheel, of a pawl-and-ratchet mechanism connected with the said cam-wheel, a gear-wheel carrying the pawl of the said mechanism, a train of gear-wheels in mesh with the said gear-wheel, and a knob-spindle

carrying a pinion in mesh with the said train of gear-wheels, substantially as shown and described.

12. In a combination-lock, the combination, with a dial, of three pointers adapted to indicate on the said dial, and mechanism, substantially as described, for turning two of the

said pointers in both directions and one in only one direction, as set forth.
